IMPEDANCE ELEMENT

Frederick P. A. Wagner, Atco, N. J., assignor to
The Brown Instrument Company, Philadelphia,
Pa., a corporation of Pennsylvania

Application May 1, 1941, Serial No. 391,319

10 Claims. (Cl. 201—67),

This invention relates to resistance elements or analogous structures for use in electrical circuits. More specifically this invention relates to resistance elements for use as calibrating resistances in precision electrical instruments or for use as the temperature responsive elements in resistance thermometers.

In prior resistance elements of this general type, resistance wire was wound in a single layer, or in a plurality of uniform layers, on a rigid core of Bakelite or similar material. The wound resistance was then coated with varnish or a similar substance to hold it in place and to protect it from the deleterious effects of moist atmosphere. These prior constructions were far from being satisfactory because in a very short time the varnish or like substance cracked open, the windings separated at points which eventually resulted in open circuits, shorts, or grounds, the winding became loose and fell apart, and such resistance constructions retained their original calibration for only a very short time. The above faults, it has been found, were caused primarily by the widely differing amounts of linear expansion and contraction of the core member and the winding taken as a unit, and the shrinkage of the varnish or such similar substance with which the windings were coated. Varnishes, lacquers, and like materials continue to shrink for a long period of time after they are initially dried which fact helped to introduce mechanical stresses and strains which caused changes in the original calibration and the eventual failures in such resistances as described above.

The prime object of this invention is to provide a new and improved moistureproof resistance element which obviates the above difficulties.

In carrying out this invention resistance material in the form of insulated wire, such as Formex insulated wire, is eccentrically bank wound on a relatively flexible core which may take the form of a woven glass fibre tubing. If desired a sleeve of like material may enclose the wound wire. Due to this arrangement an element is formed which has a relatively large number of interstices existing throughout the entire structure. These interstices are filled with an impregnating material such as varnish, lacquer or the like. The impregnated structure is then cured by baking to form a moisture impervious resistance element. Due to the large number of interstices in the resistance construction the mass by volume of the structure is largely impregnating material so that the temperature coefficient of

expansion of the resistance construction as a whole is controlled by the impregnating material. Due to the yielding characteristics of the relatively flexible core and sleeve and the eccentrically bank wound wire, the resistance construction as a whole may freely expand and contract upon temperature change without loosening or stretching the wire winding or cracking the impregnating material. Stresses and strains due to shrinking of the impregnating material are herein avoided since such shrinkage takes place uniformly throughout the entire structure both inside and out.

In addition to it being an object of this invention to overcome the mechanical and electrical faults as hereinbefore mentioned, it is an object of this invention to provide an improved type of moistureproof resistance element which will withstand unusually severe conditions of vibration without mechanical failure or change in calibration.

It is a further object of this invention to provide an entirely new type of resistance thermometer bulb which will possess the rugged long lasting qualities enumerated above, which are especially important when the element is to be used under wide and frequent temperature variations, and to provide a resistance thermometer bulb which will have little thermal capacity, be interchangeable with older types of bulbs now in use and be more economical to manufacture.

A further object of this invention is to provide a new and novel method of making improved resistance elements more economically.

The various features of novelty which characterize this invention are pointed out with particularity in the claims annexed to and forming a part of this specification. For a better understanding of the invention, however, its advantages and specific objects obtained with its use, reference should be had to the accompanying drawing and descriptive matter in which is illustrated and described a preferred embodiment of the invention.

45 Of the drawing:

Fig. 1 is an elevation partly in section illustrating an element constructed in accordance with the teachings of this invention;

50 Fig. 2 is an enlarged view showing a preferred manner of winding;

Fig. 3 is similar to Fig. 2 showing a bifilar winding;

55 Fig. 4 is a modification of Fig. 1 illustrating a lead construction desirable when the resistance

element is used as a calibrated resistance element;

Fig. 4A is an end view of Fig. 4; and

Fig. 5 is a modification, in part, of Fig. 1 showing the addition of a second resistance for shifting the characteristic of the resistance element material.

Referring to Fig. 1 of the drawing the resistance element constructed as illustrated consists of a core member 1 which may be made from a piece of woven glass fibre tubing. On the core 1 is shown a winding 2 comprising suitably insulated wire, or wires, having such electrical characteristics as it may be desirable for the resistance element to possess. The winding 2 may be covered with a larger piece of woven glass tubing 3 and the ends bound with thread as at 4, to prevent their fraying. The whole assembly is impregnated with a suitable varnish, lacquer, or like substance to stiffen and provide protection for the resistance element. Insulated lead wires 5, for connecting the element in a circuit, may be anchored directly in the tubing 1 as at 6 and connected, as by soldered joints 7, to extended portions 8 of the resistance wire 2.

As has been mentioned before the actual materials used in the construction of a resistance element in accordance with the principles of this invention are many and the invention may be practiced with varying degrees of satisfactory operation depending upon the materials selected and the manner of associating them. It has been found, however, that for the core member 1 that woven glass fibre tubing, using a basket type weave, is preferable for many reasons. In the first place glass fibre is quite flexible and hence will yield and not crack. The diagonal direction in which the fibres lie provide greater longitudinal strength to the structure and the looseness of the weave provides larger interstices to take up the impregnating material. The use of a tubular fabric sleeve possessing a diagonal pattern of weave, as illustrated in the drawings, has the further advantage of being able to more readily expand and contract along its longitudinal axis in response to internal forces. Glass fibre has the additional advantage of being able to withstand any temperatures which the now known suitable impregnating materials will withstand, which fact is important in resistance thermometer applications. Glass fibre also has a low specific heat while its ability to conduct heat is good.

For resistance thermometry applications Formex insulated wire has been found preferable because its heat transfer characteristics are better than silk and the like. It is also desirable because the volume of the winding is reduced.

The term "eccentrically bank wound" is meant to express a method of winding resistance elements which to the inventor's knowledge has never been used for this purpose before. Formerly when making resistances by winding wire on a form, the wire was wound in uniform layers one layer on top of the other. It has been found that by starting the winding at one end of the form and in a sort of random fashion immediately building the winding up to its full thickness and then progressing linearly along the form in a manner to maintain this thickness more or less progressively constant, as the winding progresses, that a winding having more numerous and larger interstices is developed. As with the woven type of core material the many and larger interstices of this type of winding will take up the impregnating material more readily and in larger

amounts than will a layer built winding. A winding of this character further possesses the advantage of being able to shift or separate, to some extent, linearly without being placed under circumferential strain and hence will neither break or be altered in cross section.

In Figure 2 an enlarged section view is used to illustrate this method of winding. The wire 2 is wound on the core 1 and the reference numerals on the cross sectioned ends of a group of turns indicate the physical position of each turn as it might be placed on the form. Since the winding is of a random character the only proviso being that its average progress is additive linearly at whatever uniform thickness is chosen, the numbers are not meant to set a definite pattern. It is found that with this type of winding an added amount of longitudinal strength results. It may be noted that the free end of the wire when wound as described will always be at the end of the resistor opposite to that end where the winding is started which in some instances is a distinct advantage.

A bifilar winding is illustrated in Fig. 3. This application of an eccentrically bank wound type of winding is essentially the same as that shown in Fig. 2. A pair of wires are handled as if they were one, but each is numbered separately. When this winding is finished it is much easier to calibrate than the previously known layer built windings. Usually an excess amount of wire is placed on the core or form when winding resistance elements so that it is only necessary to remove the excess when calibrating the resistance. With the practice of the winding features of this invention the removal of excess wire in calibrating is simplified and does not alter the fact that the connection of the two wires will always be at the end opposite to that at which the winding was started.

In Fig. 4 and Fig. 4A of the drawing a modified form for connecting the element in a circuit is illustrated. Leads 6A comprising suitable wire or strips may pierce the sleeve 3 and core 1 near the end of the resistance element, cross to the side of the core opposite the point at which they enter, and there may be securely clamped in the core member 1 by piercing the core member 1 in two places and bending the leads over as shown. The ends of the resistance wire 2 may be secured to these leads as by soldering extended portions 8 to them and when the unit has been impregnated and dried, strong substantial leads are available for its connection to a circuit.

Because of their low thermal capacity, their rapid heat transfer characteristics, their ability to withstand severe vibration and their ability to withstand large and rapid temperature changes without change in calibration or mechanical breakdowns, resistance elements constructed in accordance with this invention are especially good for resistance thermometry work.

In constructing a resistance in accordance with the principles of this invention for use as a resistance thermometer the wire 2 as shown in the drawings may be nickel or any other material which has an appreciable temperature coefficient of resistance.

As illustrated the elements of Figs. 1 and 4 have been shown with the outer sleeve 3 covering the resistance windings. Omission of this outer sleeve 3 will further increase the responsiveness of the element to changes in temperature and in such applications wherein the additional protection afforded by the sleeve is not needed, it may be

omitted without incurring any loss of the other advantages of this invention.

In constructing a resistance in accordance with the principles of this invention for use as a calibrating resistance for an instrument such as a potentiometer, Wheatstone bridge or the like the wire 2 as shown in the drawing may be of manganin or a like material having a temperature coefficient of resistance which is substantially zero.

In Fig. 5 of the drawings part of an element like that illustrated in Fig. 1 is shown with the addition of a second coil of resistance wire 10. The wire 10 may be manganin wire or the like and be connected in series with the wire 2 by a soldered connection 11 and in an amount sufficient to shift the characteristic curve of the resistance wire 10 to a desired value. The calibration of a resistance element constructed in this manner is simplified since excess wire may conveniently be removed from either the wire 2 or the wire 10 without disturbing the relation of the free ends for connection. If desired the wire 10 need not be connected to the wire 2 but may be supplied with separate leads, be composed of any material and serve any desired purpose.

While in accordance with the provisions of the statutes, this invention has been illustrated and described in the best form now known, it would be apparent to those skilled in the art that changes may be made in the form of the apparatus disclosed without departing from the spirit of this invention as set forth in the appended claims, and that in some cases certain features of this invention may sometimes be used to advantage without a corresponding use of other features.

Having now described this invention, what I claim as new and desire to secure by Letters Patent is:

1. An electrical impedance device including in combination, a random wound multi layer electrical impedance element which when untreated and unmounted is readily and freely extensible and collapsible along at least one of its axes, a porous member upon which said element is mounted, said porous member when untreated being likewise extensible and collapsible along the same axes along which said electrical impedance element is extensible and collapsible, and a protective material with which said element and said porous member are impregnated acting to predominantly control the incremental expansion and contraction of both the electrical impedance element and said porous member along their corresponding extensible and collapsible axes to prevent cracking of said protective material or the development of a condition of strain at any point between said element and the adjacent portion of said porous member.

2. An electrical impedance device including in combination, a random wound multi layer electrical impedance element which when untreated and unmounted is readily and freely extensible and collapsible along at least one of its axes, a woven glass fabric member upon which said element is mounted, said woven glass fabric member when untreated being likewise extensible and collapsible along the same axes along which said electrical impedance element is extensible and collapsible, and a protective material with which said element and said woven glass fabric member are impregnated acting to simultaneously control the incremental expansion and contraction of both the electrical impedance element 70 and

and said woven glass fabric member along their corresponding extensible and collapsible axes to prevent cracking of said protective material or the development of a condition of strain at any point between said element and the adjacent portion of said woven glass fabric member.

3. A wound wire electrical device including in combination, an elongated woven fabric core member which when untreated is readily and freely extensible and collapsible along its longitudinal axis, wire random wound on said elongated woven fabric core member around the longitudinal axis thereof to form a multi layer winding thereon, and a protective material with which said elongated woven fabric core member and said winding are impregnated acting to simultaneously control the incremental expansion and contraction of the elongated woven fabric core member and the winding thereon along the longitudinal axis thereof to prevent cracking of said protective material, or the development of a condition of strain at any point between said elongated woven fabric core member and said winding.

4. A wound wire electrical device including in combination, a tube of woven glass fabric which when untreated is readily and freely extensible and collapsible along its longitudinal axis, wire random wound on said tube of woven fabric around the longitudinal axis thereof to form a multi layer winding thereon, and a protective material with which said tube of woven fabric and said winding are impregnated acting to simultaneously control the incremental expansion and contraction of the tube of woven fabric and the winding thereon along the longitudinal axis thereof to prevent cracking of said protective material, or the development of a condition of strain at any point between said tube of woven fabric and said winding.

5. A wound wire electrical device including in combination, an elongated core member which when untreated is readily and freely extensible and collapsible along its longitudinal axis, wire wound in random fashion on said elongated core member around the longitudinal axis thereof to form a multi layer winding thereon which when untreated is more readily extensible along said axis and a protective material associated with said elongated core member and said winding and acting to predominantly control the incremental expansion and contraction of the elongated core member and the winding thereon along the longitudinal axis to prevent cracking of said protective material, or the development of a condition of strain at any point between said elongated core member and said winding.

6. A wound wire electrical device including in combination, a tube of woven fabric which when untreated is readily and freely extensible and collapsible along its longitudinal axis, wire wound in random fashion on said tube of woven fabric around the longitudinal axis thereof to form a multi layer winding thereon which when untreated is more readily extensible along said axis and a protective material associated with said tube of woven fabric and said winding and acting to simultaneously control the incremental expansion and contraction of the tube of woven fabric and the winding thereon along the longitudinal axis to prevent cracking of said protective material, or the development of a condition of strain at any point between said tube of woven fabric and said winding.

7. A wound wire electrical device including in

combination, a first tube which when untreated is readily and freely extensible and collapsible along its longitudinal axis, wire random wound on said first tube around the longitudinal axis thereof to form a multi layer winding thereon, a second tube covering said winding said second tube in its untreated condition having extensible and collapsible characteristics similar to those of said first tube, and a protective material with which said first tube, said winding, and said second tube are impregnated acting to predominantly control the incremental expansion and contraction of the first tube, the winding thereon, and the said second tube along the longitudinal axis thereof to prevent cracking of the said protective material, or the development of a condition of strain at any point between said first tube, said winding, and said second tube.

8. A wound wire electrical device including in combination, a first tube of woven fabric which when untreated is readily and freely extensible and collapsible along its longitudinal axis, wire random wound on said first tube of woven fabric around the longitudinal axis thereof to form a multi layer winding thereon, a second tube of woven fabric covering said winding, said second tube in its untreated condition having extensible and collapsible characteristics similar to those of said first tube of woven fabric, and a protective material with which said first tube of woven fabric, said winding, and said second tube are impregnated acting to simultaneously control the incremental expansion and contraction of the first tube of woven fabric, the winding thereon, and the said second tube of woven fabric along the longitudinal axis thereof to prevent cracking of the said protective material, or the development of a condition of strain at any point between said first tube of woven fabric, ⁴⁰

said winding, and said second tube of woven fabric.

9. The method of making a multi layer wound wire electrical device which is substantially unaffected by the expansion and contraction of any of its parts comprising the steps of, supporting a longitudinally extensible and collapsible tube on a mandrel, winding wire on the tube to form the electrical device by starting the winding at one end of the tube and in random fashion immediately building the winding up to its full thickness and then progressing linearly along the length of the tube in a manner to maintain this thickness substantially constant as the winding progresses, and treating the wire wound tube with a relatively large amount of protective material to cause the shrinkage and the thermal coefficient of expansion and contraction of the electrical device as a whole to be predominantly controlled by the protective material.

10. The method of making an electrical impedance element which is substantially unaffected by the expansion and contraction of any of its parts including the steps of, arranging a conductor of electricity in a random manner upon a first member which when untreated is extensible and collapsible along one of its dimensions so that approximately all of said conductor is free to move in unison with incremental movements of said first member upon the extension or collapse thereof, covering said conductor of electricity with a second member having extensible and collapsible characteristics like those of said first member, and treating the assemblage of said first member, said conductor of electricity, and said second member with a relatively large amount of protective material which controls the movement of said first member, said conductor, and said second member.

FREDERICK P. A. WAGNER.
